HENRY E. VAN NESS, OF ELMIRA, NEW YORK

DYEING APPARATUS

Original application filed April 3, 1923, Serial No. 629,633. Divided and this application filed December 30, 1925. Serial No. 78,323.

This invention relates to apparatus for impregnating parts of an absorbent mass with a liquid, and more particularly to apparatus for dyeing limited parts of a mass of yarn.

5 In my co-pending application filed April 3, 1923, Serial No. 629,633, of which the present application is a division, I described an apparatus or machine for dyeing predetermined parts of a mass of yarn which included 10 means for directing the dye into the mass while at the same time preventing it from spreading over the surface of the mass. The present application relates to specific means adapted for that purpose and for other uses.

15 The nature of the present invention will be clearly understood from a detail description of a practical yarn dyeing machine embodying it. Such a machine is illustrated in the accompanying drawings, in which:

20 Fig. 1 is a plan view of the machine; Fig. 2 is an enlarged vertical section of the pump and the injector of the machine taken on the plane of the axis of the pump cylinder and the axis of the injector; and 25 Fig. 3 is an enlarged side view partly in section showing a modified injector.

The yarn spotting machine shown in Fig. 1 comprises a base plate B on which are mounted a dye tank T and pump P and a 30 work holder W. In the use of the machine, a cone C of yarn is supported on the work holder W and measured quantities of liquid dye drawn from the tank T are forced into the cone by the pump P through the injector 35 J which is mounted on the cylinder of the pump.

The pump P has a cylinder P¹ in the bore of which are located a valve sleeve P¹⁵ and a plunger P²⁰, which may be reciprocated by means of a handle P¹⁵ connected with them through a cam P¹⁰. The pump cylinder is provided with an intake opening P⁶ connected with the tank T, an air vent opening P⁷ 40 and a discharge opening P⁸, which are controlled by openings in the valve sleeve P¹⁵ in such manner that a measured quantity of liquid dye is allowed to run into the pump cylinder when the handle P¹⁵ is in raised position, and is forcibly ejected through the dis-

charge opening P⁸ when the handle P¹⁵ is pressed downward.

The present invention relates particularly to apparatus provided for directing the limited quantities of liquid which are ejected from the pump into a mass of yarn supported on the work holder. Such apparatus I have for the sake of brevity termed the injector. The injector J comprises a nozzle J¹ and a needle J² fixed in the discharge opening of the nozzle. The nozzle J¹ has a body J³ on the rear end of which is a threaded stem J⁴ which is screwed into a tapped hole P⁵⁵ in the pump cylinder P¹. This hole P⁵⁵ communicates with the discharge opening P⁸ of the pump. The stem J⁴ contains an axial bore J⁶. The central portion of the body J³ of the nozzle provides a flange J⁸ which is seated against a boss P⁵⁶ on the cylinder P¹. In an enlarged bore in the front portion of the body J³ is seated the enlarged rear end of the needle J² which is retained in the body by a nut J¹² screwed on the front end of the body. On the outer end of the nut J¹² is a stop J¹⁵ providing an annular surface J¹⁶.

The needle J² contains a longitudinal passage J¹⁹ which extends substantially its entire length and communicates with the bore J¹¹ of the nozzle. The needle is provided with a plurality of lateral openings J²⁰ to permit egress from this passage throughout substantially the entire length of the projecting portion of the needle.

Means are provided for preventing the liquid which is forced into the injector from spreading over the surface of the mass into which it is to be injected. The rear portion J²¹ of the longitudinal passage J¹⁹ is closed and is preferably of greater cross-section than the front portion of this passage. When an injection is made with the injector J, the needle J² is thrust into the mass to such an extent that the rearmost of the openings J²⁰ is within the surface C¹ of the mass. When the needle is in this relation to the mass, the walls of the closed portion J²¹ of the passage J¹⁹ serve to prevent a spreading of the liquid over the surface of the mass.

The needle J² shown in Fig. 3 is similar

to the needle J^2 except that an open groove J^{20} replaces the lateral openings J^{20} . When an injection is made with the needle J^{21} , it is thrust into the mass to such an extent that the closed portion J^{21} of its passage extends slightly inside the surface C^1 of the mass.

The work holder W is adapted to support a wound mass of yarn for movement towards and away from the injector to bring the mass into and out of operative relation therewith. These movements are in directions parallel to the axis of the injector, that is, of its discharge opening J^{11} and consequently parallel to the needle J^2 of the injector.

A cone of yarn is mounted on a shaft W^1 carried by a plate W^6 which is slidably mounted on two bars W^7 which extend parallel to the needle J^2 . The bars W^7 are mounted on a frame W^8 which is mounted on the base plate B of the machine. A lever W^{10} is provided for causing sliding movements of the plate W^6 on the bars W^7 . An adjustable stop W^{14} is provided for limiting inward movements of the plate W^6 . This stop is set to prevent the plate W^6 from moving inward to an extent sufficient to bring the point J^{18} of the needle J^2 into contact with the shaft W^1 , as such contact would injure the point of the needle. The stop W^{14} , however, does not arrest inward movement of the plate W^6 until the mass of yarn has been pressed firmly against the stop J^{15} .

The use of the machine which has been described is as follows: A cone C of yarn to be spotted is placed on the shaft W^1 of the work holder W . The lever W^{10} is then thrown to the left, moving the cone C towards the injector J and causing the needle J^2 to penetrate the cone of yarn. The movement of the cone of yarn and the plate W^6 is arrested when the surface C^1 of the cone C comes into firm contact with the surface J^{16} of the stop J^{15} . As the mass of yarn is compressible, the part of the mass which is brought against the stop J^{15} is somewhat compressed, as shown by the dotted line in Figs. 2 and 3, when the motion of the plate W^6 is stopped. The rearmost of the openings J^{20} in the needle is within the surface C^1 of the mass. A measured quantity of liquid dye is then formed into the cone of yarn by depressing the pump handle P^{45} . The dye enters the mass of yarn through the lateral openings J^{20} in the needle and spreads by absorption so as to color the portion of the mass surrounding the needle. The lever W^{10} is then thrown to the right, moving the cone of yarn away from the injector so that the needle is withdrawn from the cone. The cone of yarn may then be turned or moved so as to bring other parts of its surface opposite the injector in order that other portions of the mass may be dyed in a similar manner.

I wish it clearly understood that my in-

vention is by no means limited to the specific apparatus described.

What I claim is:

1. In apparatus of the class described, the combination of a needle form to provide a longitudinal passage which is enclosed near the rear end of the needle and to permit lateral egress from said passage through a substantial portion of the length of the needle, and means for thrusting the needle into an absorbent mass so as to bring the front end of the enclosed portion of the passage within the surface of the mass.

2. In apparatus of the class described, the combination of a needle formed to provide a longitudinal passage which is enclosed near the rear end of the needle and to permit lateral egress from said passage through a substantial portion of the length of the needle, a support for an absorbent mass, means for causing relative movement between the needle and the support to thrust the needle into the mass, and means for stopping such movement when the front end of the enclosed portion of the passage is slightly inside the surface of the mass.

3. Apparatus of the class described, comprising a needle having a central longitudinal passage which is enclosed near the rear end of the needle, lateral openings from said passage located along a substantial portion of the length of the needle, and means for thrusting the needle into an absorbent mass to bring the rearmost of said lateral openings inside the surface of the mass.

In testimony whereof I have hereunto set my hand.

HENRY E. VAN NESS.
